UNITED STATES PATENT OFFICE.

ROY A. COCHRAN, OF AUSTIN, TEXAS, ASSIGNOR TO AMERICAN WATER HEATER CO.,
OF HOUSTON, TEXAS, A CORPORATION OF ARIZONA.

DESIGN FOR A WATER-HEATER.

48,668.

Specification for Design.

Patented Mar. 7, 1916.

Application filed September 24, 1915. Serial No. 52,531. Term of patent 7 years.

To all whom it may concern:

Be it known that I, Roy A. COCHRAN, a citizen of the United States, residing in Austin, Travis county, Texas, have invented a new, original, and ornamental Design for Water-Heaters, of which the following is a specification, reference being had to the accompanying drawings, forming part thereof.

The figure is a side elevation of a water heater, showing my new design.

I claim:

The ornamental design for a water heater as shown.

ROY A. COCHRAN.

In the presence of—

J. C. COCHRAN,
R. H. McCUTCHEON.
